UNITED STATES PATENT OFFICE

JOHN H. LAMB, OF PIEDMONT, WEST VIRGINIA

ICE-CAN.

1,157,943.

Specification of Letters Patent.

Patented Oct. 26, 1915

Application filed January 29, 1915. Serial No. 5,125

To all whom it may concern:

Be it known that I, JOHN H. LAMB, a citizen of the United States, and residing at Piedmont, in the county of Mineral and State of West Virginia, have invented certain new and useful Improvements in Ice-Cans, of which the following is a specification.

This invention relates to certain new and useful improvements in ice cans.

The primary object of this invention is to provide a can serviceable in the manufacturing of ice and adapted for insuring the formation of a solid ice block and obviating any flaws or central feathers commonly found in what is known as "tombstone" ice.

A further object is to provide a can adapted for the reception of water for freezing into ice, the can being provided with a centrally vented aerating member recessed within the can bottom and continuously operable during the formation of the ice block within the can.

It is also designed to form completely solid ice blocks which shall be uninterrupted by any aerating pipes as sometimes employed projecting from above and into the freezing water, the present can providing a continuous upward central air flow through the water completely preventing any formation of a core within the ice block and rendering the ice of uniform density throughout the block and readily removable from the can at the completion of the freezing operation.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like designating characters refer to corresponding parts throughout the several views: Figure 1 is a perspective view of a portion of the tank room of an ice manufacturing plant and illustrating the present device in use upon some of the ice cans positioned therein. Fig. 2 is a top plan view of a can constructed in accordance with this invention. Fig. 3 is a perspective view of the same partially broken away. Fig. 4 is a vertical diagonal

sectional view through the can partially broken away and illustrated as connected to the air line. Fig. 5 is a side elevation of two ice cans with the mounting frame-work broken away and illustrating one can connected to the main air header and the other can to the branch line, and, Fig. 6 is an enlarged detail sectional view through a portion of the can bottom and the aerating pipe positioned therein.

Referring more in detail to the drawings, the present form of ice can, it will first be noted, is designed for employment in the tank room of an ice manufacturing plant arranged substantially in the usual manner and illustrated in Fig. 1, provided with removable tops 10 overlying the tank frames 11, each of the said frames adapted to receive one of the ice cans loosely therein.

The present form of ice can is an open topped tapering can 12 of the desired dimensions and provided with an air agitating pipe 13 permanently secured thereto and adapted for aerating the water which is placed within the can for the purpose of freezing the same. The said pipe 13 extends within the can nearly to the top thereof and is positioned engaging one of the can corners 14 while a covering protecting strip 15 is provided within the can overlying the upright portion of the pipe and being soldered to the adjacent side walls of the can. A lower angular extension 16 of the pipe 13 is embedded within a valley of groove 17 struck downwardly from the can bottom 18 and the said extension being positioned therein is preferably secured by solder 19, which provides a substantially smooth upper surface for the can bottom. The can bottom adjacent the inner open end or mouth 20 of the pipe extension has a central socket 21 therein, thus allowing the free exit of the air from the pipe which is adapted to rise through the water within the can for continuously aerating and agitating the water during the freezing operation.

It will be understood that when the can 12 is first positioned within the tank frame 11 that water will be gradually led into the can which will allow the can to lower from the position illustrated at 22 in Fig. 5 of the drawings to its position shown at 23 therein, in which latter position, the can is maintained until the freezing of the contained water is consummated.

A main compressed air pipe or header 24 is provided at a convenient point whereby the same may be connected by a short hose or drop pipe 25 with the upper end of the pipe 13 of the can during the initial filling of the can with water. This pipe may be removed whenever desired, being preferably detachably connected by means of a connection not shown, with a main supply pipe. 10 When the can settles sufficiently, an auxiliary air main 26 is utilized for supplying air to the ice cans the hose 25 being detached from the pipe 13 and one of the similar sections of hose 27 of the auxiliary main 26 is used in the place thereof. Fig. 1 shows one of the auxiliary mains 26 arranged between two rows of tank frames to supply air to the pipe 13 of the tanks in both rows, this being also shown in Fig. 5. These mains 26 are a part of the plant and remain 20 permanently in position.

The employment of the main air header 24 initially and the auxiliary lower air main 26 during the remainder of the ice forming process insures a substantially uninterrupted upward flow of air through the freezing water over the air pipe mouth 20. Any serviceable hose connection may be provided between the upper end of the pipe 13 and the 30 lengths of hose 25 and 27, but it is herein designed to provide a ground internal seat at the upper end 28 of the pipe 13, into which a metallic plug 29 carried by the free end of the said hose sections may be readily 35 inserted for forming an air-tight joint, although being readily manually disconnected therefrom. A turn plug is provided for each hose connection for controlling the flow of air to the cans. The injection of air into the can from main 24 serves to prevent the water from freezing in the arms or branches 13-16 of the angular pipe, and the air fed through the pipe to the center of the can bottom prevents white or opaque ice from 45 forming in the walls of the can during the filling operation.

It will thus be seen that a serviceable ice can is provided which is employed with the tank frames in substantially the manner 50 now used in ice factories but which by reason of the novel form of can, inures to the perfect operation of the system in insuring an output of perfect ice blocks of uniform density, and which blocks are thus readily 55 formed within the cans and are easily removed therefrom when the freezing operation is completed.

While the form of the invention herein shown and described is what is believed to 60 be preferable embodiment thereof, it is nevertheless to be understood that minor changes may be made without departing

from the spirit and scope of the invention as claimed.

What I claim as new is:—

65

1. An ice can comprising an open topped receptacle having a groove in the bottom thereof extending from the center of the bottom to one corner thereof, and an angular air-admission pipe having the horizontal 70 arm thereof seated in said groove and the vertical arm nested in one corner of the receptacle and extending upwardly to a point near the top of the receptacle, the receptacle bottom having a socket at the open outer 75 end of the horizontal arm of the angular pipe to permit free egress of air from said pipe.

2. An ice can comprising an open topped receptacle having a diagonally arranged 80 groove downwardly struck in the bottom thereof and terminating centrally of the said can, an air inlet pipe positioned within said can and extending outwardly engaging the corner thereof and provided with an inner 85 angular extension seated within the said groove and terminating in an open mouth adjacent the end of said groove, and a strip overlying the said corner positioned pipe and secured to the adjacent sides and bottom 90 of the said can.

3. A device of the class described, comprising in combination with a tank frame having an upper and a lower air line conduit positioned adjacent thereto, an ice can slidably positioned within the said frame, an angular air pipe secured within the said can at a corner portion thereof and having an angular extension terminating in an open mouth centrally of the bottom of the said 100 can, and removable hose connections for the said air pipe and carried by the said conduits.

4. A device of the class described, comprising in combination with a tank frame and an upper and lower compressed air supply conduit, hose-connecting means carried by each of the said conduits, metallic plug connectors at the free ends of the said means, an ice can removably positioned within the said frame and having a diagonally-arranged groove in the bottom thereof, an air pipe within said can and secured to a corner thereof and having a terminal angular extension seated within the said groove and terminating in an open mouth adjacent the 110 inner end of the latter, the upper end of the said pipe being provided with a ground connector receiving seat.

105

In testimony whereof I affix my signature in presence of two witnesses.

JOHN H. LAMP
